UNITED STATES PATENT OFFICE

169,427

TELEVISION RECEIVER CABINET

Jack De Young, Grand Haven, Mich., assignor to
Zenith Radio Corporation, a corporation of
Illinois

Application May 10, 1952, Serial No. 19,680

Term of patent 14 years

(Cl. D56—4)

To all whom it may concern:

Be it known that I, Jack De Young, a citizen of the United States, residing at Grand Haven, in the county of Ottawa, State of Michigan, have invented a new, original, and ornamental Design for a Television Receiver Cabinet, of which the following is a specification, reference being made to the accompanying drawing, forming a part thereof.

Fig. 1 is a perspective view of a television receiver cabinet showing my new design.

Fig. 2 is a cross-sectional view thereof on line 2—2 of Fig. 1.

The design of the side of the cabinet not shown

is similar to the design of the side shown. The design of the rear portion of the cabinet, not shown, is open.

I claim:

The ornamental design for a television receiver cabinet, as shown and described.

JACK DE YOUNG.
